UNITED STATES PATENT OFFICE

ARTHUR D. ROESE AND FLORENTINO G. L. REA, OF MOUNT CLEMENS, MICHIGAN

DESIGN FOR AN ICE-CREAM-CONE TRAY

Application filed November 29, 1929. Serial No. 33,587. Term of patent 7 years.

To all whom it may concern:

Be it known that we, ARTHUR D. ROESE, a citizen of the United States, and FLORENTINO G. L. REA, a citizen of the Argentine Republic, both residing at Mount Clemens, in the county of Macomb and State of Michigan, have invented a new, original, and ornamental Design for Ice-Cream-Cone Trays, of which the following is a specification, reference being had to the accompanying drawing, forming part thereof.

Fig. 1 is a plan view showing our new design of tray for ice cream cones.

Fig. 2 is an edge view thereof.

We claim:

The ornamental design for an ice cream cone tray as shown.

ARTHUR D. ROESE.
